UNITED STATES PATENT OFFICE.

RUDOLPH M. HUNTER AND JAMES T. STEWART, OF PHILADELPHIA, PA.

PROCESS OF AND APPARATUS FOR PACKING BRAN.

SPECIFICATION forming part of Letters Patent No. 280,478, dated July 3, 1883.

Application filed May 21, 1883. (No model.)

To all whom it may concern:

Be it known that we, RUDOLPH M. HUNTER and JAMES T. STEWART, of the city of Philadelphia, county of Philadelphia, and State of Pennsylvania, have invented an Improvement 5 in Process and Apparatus for Packing Bran, of which the following is a specification.

Our invention has reference to processes and apparatus for packing bran; and it consists in 10 heating the bran and then compressing it into the desired-sized packages or boxes, and, if desired, extracting all excess of air during the process of packing, and in apparatus for carrying on said process, all of which is more fully 15 set forth in the following specification and shown in the accompanying drawings, which form part thereof.

Heretofore it has been found difficult to compress bran to a sufficiently compact form to 20 make its transportation and sale of commercial value. This non-compressibility is due to the fact that the flaky cuticle is so constituted that it becomes electrified, and all the particles repel each other, causing the air to be interposed, 25 and thus rendering it difficult of compression. When this electrical condition is destroyed the bran may be compressed to an enormous extent, and this may be increased by extracting the greater part of the air inclosed by the said 30 bran particles.

The object of our invention is therefore to provide a process and apparatus by which the electrical condition of the bran may be destroyed, and, if desired, the air removed, and 35 then compress the said bran and seal it, when compressed, into a case or package.

In the drawings, Figure 1 is a sectional elevation of our improved apparatus for compressing bran, and Fig. 2 is a sectional elevation 40 of a case of packed bran.

A is a hopper, into which the bran is fed, and from which it passes into the cylinder B, which may be heated externally by a steam-jacket, B'. Working through this cylinder B 45 is a feed-screw, C, formed of a hollow shaft, C', provided with a screw formed of pipes C² or a hollow sheet-metal spiral, through which steam is passed. This hollow shaft C' is supported at the bottom by bearing D, made with an annular space, d, into which steam is fed by steam-pipe E, and from which it passes into the hol-

low axle or shaft C' by apertures e. This bearing is provided with an adjustable bearing-block, d', made adjustable by a screw, d². This shaft C' is also supported in a similar bearing 55 at the top, the only difference being in the omission of the block d', as this element is not needed. This shaft or axle C' is provided on or near the top with a bevel-gear wheel, F, which meshes with a small bevel-wheel, F', secured to driving-shaft F², which also carries a small pinion, G, which meshes with a large spur-wheel, G', carried loosely on a shaft, H, the object of which will be presently explained.

B² is the outlet from the cylinder B, and 60 opens into another cylinder, I. This outlet or part of it may be made of fine wire-gauze b, through which air may be sucked by a fan, J, and trunk J', and any particles of dust, &c., extracted may be collected in a dust-chamber, 70 J'. To prevent clogging of the gauze, open metal fingers b', or their equivalent, are constantly vibrated, for instance, by a shaft, b², crank b³, rod b⁴, and crank-wheel b⁵.

The bottom part of cylinder I is made with 75 a small flange, i, to fit over the top of the packing-case K, and, if desired, gauze-covered openings I' may be made in the said cylinder near its bottom, and also, if desired, in the bottom of compressing-plunger L, which reciprocates in said cylinder. This cylinder I is so formed as to leave a slot across its front when the plunger L is fully raised, as at I², through which the case-lid K' may be inserted between the bran and plunger. The plunger 80 is made with a guide-pin, M, provided with nuts m at the top, and upon which is a head, N, which is kept pressed against said nuts with great force by a spring, O. P is a pitman connecting the head N with the crank Q, 90 which is secured upon the shaft H, which is provided with a sliding clutch, H', which may be engaged with spur-wheel G' when the crank Q is to be rotated by a lever, R, which may be operated by hand. A spring, R', 95 throws the clutch out of contact and arrests all motion when the lever R is released. If desired, this crank might be made so as to simply make one revolution and then come to rest each time the lever R was pulled; but this is common in many mechanical devices.

We do not limit ourselves to the particular

construction of apparatus shown, as it may be modified in various ways without departing from our invention. For instance, it is not necessary that the bran should be heated with steam heat, as hot air, gas, products of combustion, or liquid may be used in lieu of steam, and in place of using it externally it may, if desired, be brought into direct contact, though we prefer to use steam in the manner substantially as shown.

The operation is as follows: The bran is fed into hopper A, from which it passes into cylinder B, and through which it is forced by heating feed-screw C. The heat from steam-jacket B' and steam feed-screw C both heat the bran and destroy the electrical condition, allowing the said bran to pack at once. When this is taking place the bran is being continually pressed downward and compressed, and while being compressed the heated air is extracted with any fine dust, thus enabling the compression to be greatly increased. After being de-electrified and deaerated it is automatically forced into the cylinder I and case K. When filled pretty close to the plunger the lid K' is pushed into the aperture I² and rests upon said bran. The bran, when forced into cylinder I, is compact. Now, the lever R is pulled and the plunger L is forced down, compressing the bran down into the case K in the form of a hard solid mass, and when the lid is in the top of the case it is nailed in place. One of the side flanges, i, which is hinged as at i', may then be turned up and the packed case withdrawn and an empty one replaced. Triangular strips k may then be nailed on the top to keep the lid tightly on. During this last operation the bran is being compressed into the bottom of the cylinder B and outlet B², and after placing a new box in position the piston or plunger L is raised and the compressed bran falls into the new case. By this it is seen that in reality no time is lost, as the bran in the cylinder B is being de-electrified and condensed while the case is being closed. By this method of packing bran no moisture is used, and when unpacked the bran will assume its original condition, and will be found not at all impaired by the excessive compression.

We are aware of the patent to Locke, No. 223,522, for packing meat in cans, and claim nothing therein set forth or shown, our invention being limited to bran and like substances. Locke shows mechanism for forcing his meat while hot into a tin can, feeding it from the bottom upward to insure filling the can and getting rid of the air. He uses a small amount of pressure, sufficient to make the preserved meat flow into the can; but there is no attempt at compression. He also keeps his hoppers warm; but that is to prevent the meat drying on them and clogging the same. There is no electrical condition to deal with in the preserved meat. In our invention we use considerable heat and great pressure and utilize

these in a process entirely different and for a different result than Locke, and we therefore disclaim anything set forth or shown in the Locke patent.

Having now described our invention, what we claim as new, and desire to secure by Letters Patent, is—

1. The herein-described process of packing bran, which consists in first subjecting said bran to heat and then to compression, substantially as and for the purpose specified. 75

2. The herein-described process of packing bran, which consists in subjecting said bran to heat, then extracting most of the air held 80 among the particles of bran, and then subjecting said heated and deaerated bran to compression, substantially as and for the purpose specified.

3. The process for packing bran, which consists in heating said bran and simultaneously compressing the same, substantially as and for the purpose specified. 85

4. The process for packing bran, which consists in heating said bran and simultaneously compressing and deaerating the same, substantially as and for the purpose specified. 90

5. The process for packing bran, which consists in heating said bran, simultaneously compressing and deaerating the same, and finally 95 subjecting the said bran to high pressure, substantially as and for the purpose specified.

6. The herein-described process of packing bran, which consists in destroying the electrical condition of said bran and then subjecting 100 it to high pressure, substantially as and for the purpose specified.

7. The combination of feeding and heating apparatus with a compressing device, the same being organized to heat and compress 105 bran, substantially as and for the purpose specified.

8. The combination of feeding and heating apparatus with deaerating and a compressing device, the same being organized to heat and 110 compress bran, substantially as and for the purpose specified.

9. The combination of cylinder B, feed-screw C, means, substantially as described, to heat the bran in said cylinder, cylinder I, and 115 plunger L, substantially as and for the purpose specified.

10. The combination of cylinder B, feed-screw C, means, substantially as described, to heat the bran in said cylinder, gauze-covered opening b, air-trunk J', fan J, cylinder I, and plunger L, substantially as and for the purpose specified. 120

11. The combination of cylinder B, feed-screw C, means, substantially as described, to heat the bran in said cylinder, gauze-covered opening b, air-trunk J', fan J, cleaner b', cylinder I, and plunger L, substantially as and for the purpose specified. 125

12. The combination of cylinder B, feed-screw C, means, substantially as described, to heat the bran in said cylinder, case K, cylin- 130

der I, means to make a tight joint between said cylinder I and case, and plunger L, substantially as and for the purpose specified.

13. The combination of cylinder B, steam-jacket B', feed-screw C, cylinder I, and plunger L, substantially as and for the purpose specified.

14. The combination of cylinder B, steam feed-screw C, substantially as and for the purpose specified.

15. The steam feed-screw C, for heating bran,

formed of a hollow shaft, C', with the screw made of hollow metal or pipes, substantially as and for the purpose specified.

In testimony of which invention we hereunto set our hands.

RUDOLPH M. HUNTER.
JAMES T. STEWART.
